E. G. GERMER ET AL

MOLDING MACHINE

Filed Oct. 30, 1925

UNITED STATES PATENT OFFICE.

EDWARD G. GERMER, EARL G. WALBRIDGE, AND JOHN M. WYSOCKI, OF ERIE, PENN-SYLVANIA; SAID WALBRIDGE AND WYSOCKI ASSIGNEES TO SAID GERMER.

MOLDING MACHINE.

Application filed October 30, 1925. Serial No. 65,765.

This invention is designed to improve molding machines permitting the making of machines capable of handling comparatively large molds with ordinary flask and pattern plates. In carrying out the invention we provide a lifting device for the mold flask which is pivotally secured to the flask, preferably the cope, whereby the flask may be lifted so as to reverse it and the cope lifted after the removal of the pattern. The invention also contemplates the swinging of the lifted mold so that a mold may be repaired when necessary. Features and details of the invention will appear from the specification and claims.

The invention is illustrated in the accompanying drawings as follows:

Fig. 1 shows a front elevation of the machine.

Fig. 2 an end view of the machine.

Fig. 3 an enlarged view of the lifting blocks and flask pins.

1 marks the frame of the machine. This has axles 2 and the wheels 3. A pressure cylinder 4 is arranged at the center of the frame and a platform 5 is mounted on the pressure mechanism. The flask drag 6, mold plate 7 and cope 8 are shown on the platform and a pressure board 9 is shown above the flask. A squeezer head 10 is arranged above the pressure board. A squeezing valve 11 controls the pressure cylinder 4 and a controlling valve 12 controls an air line 13 connected with the vibrator 14 attached to the mold plate. Uprights 15 are pivotally mounted on pins 16 extending from the frame and the squeezing head 10 is adjustably secured on the uprights 15 by means of pins 17, the pins extending through openings 17^a in the uprights. Springs 18 extend from clips 19 on the uprights to pins 20 on the front side of the platform 5. These springs yieldingly hold the uprights 15 in their forward position, the uprights 15 engaging stops 22 in their forward position. This swinging mounting of the uprights permits the swinging of the squeezing head to a rearward position shown in dash lines in Fig. 2. So far the construction follows the common mold machine.

Uprights 21 are pivotally mounted on the pins 16 and engage the stops 22 in their forward position. These uprights have the lifting blocks 23 which are slidingly mounted

on the uprights 21. The blocks 23 are connected by links 24 with rock arms 25. The rock arms 25 are mounted on a rock shaft 26 which extends across the front of the machine so that the sliding blocks 23 are maintained in parallel relation. A foot lever 27 is fixed on the rock shaft 26 and a hand lever 28 is also fixed on the shaft 26. The hand lever operates adjacent to a notched segment 29 which is adapted to be engaged by a pawl 30 arranged in a guide 31 on the handle 28. A link 32 extends from the pawl to a trip handle 33 mounted on the lever 28. In lifting the blocks, therefore, the operator steps on the foot lever, grasps the hand lever 28 and throws the whole weight of the body on the two levers, this ordinarily being sufficient to raise even a large size mold.

Pins 34 extend through the lifting blocks 23 and are secured thereon by pins 35. These lifting pins 34 have sockets 36 at their inner ends, these sockets being adapted to receive trunnions 37 carried by brackets 38 on the cope 8. The usual locking straps, or U-bars 39 are placed over the cope and drag to lock them together when it is desired to swing them.

In the operation of the device, the mold is placed on the platform inverted, that is to say, with the drag upwardly. Sand is filled into the drag on top of the mold plate. The drag and cope are secured together by the strap 39. The flask is lifted by means of the lifting device described and turned over so as to place the drag on the bottom and lowered so as to put the mold on the platform. The cope is then filled and the mold squeezed in the usual manner. After the platform recedes from the squeezing action the head 10 is swung to the rear position shown in dash lines in Fig. 2 and the straps 39 are released and the cope raised, the jolting and vibrating being utilized in the usual manner. The parts are locked with the cope in its lifted position by the pawl 30. After the cope is lifted the uprights are swung rearwardly and this permits the cope to be swung up so that the mold can be repaired or worked as necessary. The pattern is removed from the drag and this mold can be repaired as necessary. The uprights are swung to their forward position and the cope lowered into position on the

drag so as to complete or close the mold. The mold is then removed from the platform.

In order to reduce the lifting power necessary to lift the flask we prefer to put springs 5 around the shaft 26, the springs being tensioned to exert lifting pressure on the rock arms.

What we claim as new is:—

1. In a molding machine, the combination 10 of a molding machine platform; a flask lifter adapted to lift flasks from the platform comprising means pivotally engaging a flask; and a swinging mounting for said lifter.
15. 2. In a molding machine, the combination of a molding machine platform; uprights at the sides of the platform; sliding blocks on the uprights; flask connections on the blocks; and lifting mechanism actuating the 20 blocks.
25. 3. In a molding machine, the combination of a molding machine platform; uprights at the sides of the platform; sliding blocks on the uprights; flask connections on the blocks; and lifting mechanism actuating the blocks comprising a foot lever.
30. 4. In a molding machine, the combination of a molding machine platform; uprights at the sides of the platform; sliding blocks on the uprights; flask connections on the blocks; and lifting mechanism actuating the blocks comprising a hand lever.
35. 5. In a molding machine, the combination of a molding machine platform; uprights at the sides of the platform; sliding blocks on the uprights; flask connections on the blocks; and lifting mechanism actuating the blocks comprising a hand lever and a foot lever.
40. 6. In a molding machine, the combination of a molding machine platform; uprights at the sides of the platform; sliding blocks on the uprights; flask connections on the blocks; and lifting mechanism actuating the

blocks comprising a lever, and means for locking the blocks when elevated.

7. In a molding machine, the combination of a molding machine platform; uprights at the sides of the platform; sliding blocks on the uprights; flask connections on the blocks; and lifting mechanism actuating the blocks comprising rock arms connected with the blocks, a rock shaft on which the arms are mounted, and a lever actuating the shaft.

8. In a molding machine, the combination of a molding machine platform; uprights at the sides of the platform; sliding blocks on the uprights; flask connections on the blocks; lifting mechanism actuating the blocks; and means exerting yielding pressure on the blocks.

9. In a molding machine, the combination of a molding machine platform; a flask lifter adapted to lift flasks from the platform comprising means pivotally engaging a flask; and means exerting yielding lifting pressure on the flask lifter.

10. In a molding machine, the combination of a molding machine platform; a flask on the platform having trunnions thereon; a flask lifter comprising sockets engaging the trunnions; and a swinging mounting for the flask lifter.

11. In a molding machine, the combination of a platform; a pressure device operating on the platform; a squeezing head opposing the pressure device; a swinging mounting for the squeezing head; a flask mounted on the platform having trunnions; a flask lifter operating on the trunnions; and a swinging mounting for the lifting device.

In testimony whereof we have hereunto set our hands.

EDWARD G. GERMER.
EARL G. WALBRIDGE.
JOHN M. WYSOCKI.
